Attorney*

UNITED STATES PATENT OFFICE.

GEORGE Y. EMERSON, OF ROCHESTER, NEW HAMPSHIRE.

SHOE-HEEL-ATTACHING MEANS.

Application filed September 19, 1925. Serial No. 57,388.

To all whom it may concern:

Be it known that I, GEORGE Y. EMERSON, a citizen of the United States, residing at Rochester, in the county of Strafford and State of New Hampshire, have invented certain new and useful Improvements in a Shoe-Heel-Attaching Means, of which the following is a specification.

The present invention relates generally to 10 shoes and more particularly to means for attaching the heels to the soles.

An important object of the invention is to provide means whereby the heels are attached to the heel portions of the soles without the use of nails, but by the use of fasteners whereby an unskilled person may easily take off the heel and replace another one thereon.

The above object is carried out by an exceedingly simple construction which is strong, and durable, and one which is thoroughly reliable and efficient in use, and otherwise well adapted to the purpose for which it is designed.

25 The advantage of my improvement means a great saving in time in the manufacture of the shoes and would permit a person after wearing the heels down on one side, to change the heels so that that which was previously on the right foot shoe, could be changed to the left foot shoe and vice versa, so as to wear the heels down evenly.

Another idea is that the wearer can put on his own heels without sending them to 35 the repair shop.

With the above and numerous other objects and advantages in view the invention resides in certain novel features of construction, and in the combination and arrangement of parts as will be hereinafter more fully described and claimed.

In the drawing

Figure 1 is a sectional elevation of the heel portion of a shoe embodying the features of my invention,

Fig. 2 is a bottom plan view of the heel portion of the sole, and

Fig. 3 is a detail perspective of one of the nuts.

50 Referring to the drawing in detail, it will be seen that 1 designates a sole generally having the heel portion 2 which is provided with a plurality of oblong slots 3. When the sole 1 is mounted in the usual manner on

the inner sole of the shoe as is indicated at 55 4, it will be possible to engage the nuts shown in Fig. 3 in the slots 3.

Each of these nuts includes a body portion 5 having the threaded bore 6 and a pair of laterally extending wings 8 disposed in 60 opposite directions from each other and mounted at one end of the body. These wings may be passed through the slots 3 and then the nut is twisted so that the wings extend transversely of the oblong slots between 65 the inner sole 4 and the heel portion 2 of the sole 1.

The heel 9 is provided with counter-sunk openings 10 so that screws or bolts 11 may have their heads counter-sunk therein where 70 the shanks pass thru the openings and are threadedly engaged with the threaded bores 6. It will thus be seen that the heels 9 can be easily and quickly moved or put in place on the shoe and the only tool necessary is an 75 ordinary screw driver.

It is thought that the construction, operation, and advantages of the invention will now be apparent without a more detailed description thereof. The present embodiment 80 of the invention has been disclosed merely by way of example since in actual practice it attains the features of advantage enumerated as desirable in the statement of the invention and the above description.

85 It will be apparent that changes in the details of construction and in the arrangement of parts may be resorted to without departing from the spirit or scope of the invention as herein claimed or sacrificing any of its 90 advantages.

Having thus described my invention, what I claim as new is:—

1. In a shoe including an inner sole, an outer sole having a heel portion provided with oblong slots, a plurality of nuts having laterally extending wings at one end adapted to pass through the slots so that the nuts may be turned to engage the wings between the inner and outer soles, a heel, and 100 screws passing through the heel and engaged with the nuts.

2. In a shoe including an inner sole, an outer sole having a heel portion provided with oblong slots, a plurality of nuts having laterally extending wings at one end adapted to pass through the slots so that the nuts may be turned to engage the wings between 105

the inner and outer soles, a heel, and screws passing through the heel and engaged with the nuts, said heel provided with countersunk openings for receiving the screws.

5. 3. In combination, an inner sole, an outer sole, provided with oblong slots, and a plurality of nuts having threaded bores in their

bodies and wings extending in opposite directions from one end, said wings constructed and arranged to pass through said slots ¹⁰ so that the nuts may be turned to dispose the wings between the two soles.

In testimony whereof I affix my signature.

GEORGE Y. EMERSON.
